CLAIM

The ornamental design for an aqueous ozone hand sanitation device, substantially as shown and described.

DESCRIPTION

FIG. 1 is a front top isometric view of the new design; FIG. 2 is a front bottom isometric view of the new design of FIG. 1;

FIG. 3 is a front view of the new design of FIG. 1;

FIG. 4 is a left side view of the new design of FIG. 1;

FIG. 5 is a right side view of the new design of FIG. 1;

FIG. 6 is a top view of the new design of FIG. 1;

FIG. 7 is a bottom view of new design of FIG. 1; and,

FIG. 8 is a front top isometric view of the new design of FIG. 1 in use.

The broken lines shown in the drawing are for the purpose of illustrating portions of the article and environment that form no part of the claimed design. The rear view is not visible in use, does not form part of the claimed design, and is therefore omitted.
